This application contains subject matter related to the following co-pending U.S. design patent applications:

Application Ser. No. 29/639,822, filed Mar. 9, 2018 and entitled Vehicle Wheel, Toy Vehicle Wheel, and/or Replicas Thereof; and

Application Ser. No. 29/635,621, filed Feb. 1, 2018 and entitled “Vehicle Wheel, Toy Vehicle Wheel, and/or Replicas Thereof.”

FIG. 1 is a perspective view of a vehicle wheel, toy vehicle wheel, and/or replicas thereof according to the design;

FIG. 2 is an additional perspective view thereof;

FIG. 3 is an additional perspective view thereof;

FIG. 4 is a front view thereof;

FIG. 5 is a rear view thereof in a lighter gray scale, representing environmental features that form no part of the claimed design; and,

FIG. 6 is a side view thereof.
